UNITED STATES PATENT OFFICE.

JOHN LALLY, OF BOSTON, MASSACHUSETTS.

BUILDING CONSTRUCTION.

1,329,614.

Specification of Letters Patent.

Patented Feb. 3, 1920.

Application filed August 6, 1919. Serial No. 315,577.

To all whom it may concern:

Be it known that I, JOHN LALLY, a citizen of the United States, residing at Boston, Suffolk county, Massachusetts, have invented new and useful Improvements in Building Constructions, of which the following is a specification.

My invention relates to improvements in building construction of the reinforced concrete type and constitutes an improvement on the structure of my Letters Patent No. 1,258,917, dated March 12, 1918, and it is my object to cheapen, lighten, simplify and strengthen the structure shown therein and to make additional provision for reinforcing the floor adjacent the column and provide means for holding the reinforcing bars taut and tie the columns together into a rigid, braced structure.

20 In the drawing Figure 1 is a side view of my improved construction provided with a circular crown, partly in section; Fig. 2 a top view of the structure of Fig. 1; Fig. 3 a section on the line 3—3 of Fig. 1; Fig. 4 a plan view of one form of floor reinforcing; Fig. 5 a top view of my construction with a square crown, showing the reinforcing bars and adjusting means therefor; Fig. 6 a sectional view of the structure of Fig. 5; and Fig. 7 a detail view of the reinforcing bar adjusting means.

I employ a column 1 as the foundation of my structure and provide it with a plurality of slots 2 near the top. A bracket plate 3 is inserted in each of these slots and has an upwardly extending lug 4 engaging the inside of the column above the slot. A crown 5, circular as shown in Figs. 1, 2 and 3 and square in Figs. 5, 6 and 7, is connected 40 to the brackets by struts 6 extending from the crown to the brackets. This leaves the crown open and, as the slots 2 are so located that the crown is flush with the top of the column, I am enabled to superimpose the upper story column 7 on the lower column with its base flush with the upper floor.

In practice the column 1 is filled with plastic material like concrete, thereby binding the brackets 3 in position and strengthening the structure.

50 In a building the column and crown are set up and wire reinforcing fabric 8 is laid in position to form the floor reinforcement.

Reinforcing rods of any desired shape 9 are arranged radially over the crown and 55 extend under the wire fabric to better dis-

tribute the loads and strengthen the structure where the floor joins the column.

The wire fabric, reinforcing rods, crown and outside of the column are then embedded 60 in the plastic material, generally concrete, and the resultant structure is a reinforced monolith which is not only strong, but light, and the floor space is diminished only by the outside diameter of the column.

65 In the modification shown in Figs. 5, 6 and 7 a square crown 5' is employed and is provided with a tension plate 10 on the upper face of the crown and preferably wider than the top face. This tension plate 70 has a plurality of slots 11 along its length at right angles to its long side and is secured to the crown by means of bolts 12.

The reinforcing bars 9' have hooks 13 on their ends and these hooks pass over the 75 inner edge of the tension plates and engage it.

80 After the columns have been set up the hooks 13 are placed over the tension plates of adjacent columns and anchored thereto so that on pulling up on the tension plates and bolting them in place the reinforcing bars 9' are held tautly in place and unite the columns into a self supporting, solid 85 metallic structure around which the concrete may be poured.

I claim:

1. Building construction composed of a hollow column slotted below the top, a bracket with an upwardly extending lug in 90 each slot, a crown approximately flush with the top of the column, struts connecting the crown and brackets and a plastic filling within the column engaging the brackets.

2. Building construction composed of a 95 hollow column slotted below the top, a bracket with an upwardly extending lug in each slot, a crown approximately flush with the top of the column, struts connecting the crown and brackets, a plastic filling within 100 the column engaging the brackets and plastic material covering and embedding said structure.

3. Building construction composed of a hollow column slotted below the top, a 105 bracket with an upwardly extending lug in each slot, a crown approximately flush with the top of the column, struts connecting the crown and brackets, means on the top of the column for engaging a superimposed column 110 and plastic material within said column engaging the brackets.

4. Building construction composed of a hollow column slotted below the top, a bracket with an upwardly extending lug in each slot, a crown approximately flush with the top of the column, struts connecting the top of the column, struts connecting the crown and brackets, a reinforcing fabric adjacent the top of the crown, reinforcing bars extending over and from the top of the crown and under said fabric and plastic material covering and embedding said structure.

5. Building construction composed of a column, an open top crown thereon, a tension plate adjustably secured to the crown and reinforcing bars anchored to said plate.

6. Building construction composed of a hollow column slotted below the top, a

bracket with an upwardly extending lug in each slot, a crown approximately flush with the top of the column, struts connecting the crown and brackets, a plastic filling within the column engaging the brackets, a tension plate adjustably secured to the crown and reinforcing bars anchored to said plate.

7. A plurality of adjacent columns each having an open top crown thereon, tension plates adjustably secured to the crowns, and reinforcing bars anchored to said tension plates and extending from crown to crown whereby the columns are united into an integral structure.

In testimony whereof, I have signed my name to this specification.

JOHN LALLY.
